[57] CLAIM

The ornamental design for a high chair tray, as shown and described.

DESCRIPTION

FIG. 1 is a front elevational view of a high chair tray showing a first embodiment of our new design;

FIG. 2 is a rear elevational view thereof;

FIG. 3 is a right-side elevational view thereof, with the left-side elevational view thereof being a mirror image;

FIG. 4 is a top plan view thereof;

FIG. 5 is a bottom view thereof;

FIG. 6 is a perspective view of a high chair tray showing a second embodiment in accordance with our new design;

FIG. 7 is a front elevational view thereof;

FIG. 8 is a top plan view thereof;

FIG. 9 is a right-side elevational view thereof, with the left-side elevational view thereof being a mirror image; and,

FIG. 10 is a bottom view thereof.
